(57) **CLAIM**

The ornamental design for a set of cup and cup holder, as shown and described.

DESCRIPTION

FIG. 1 is a top perspective view of a set of cup and a cup holder;

FIG. 2 is a front elevational view thereof of the set of cup and the cup holder shown in FIG. 1;

FIG. 3 is an exploded top perspective view thereof;

FIG. 4 is an exploded side elevational view thereof;

FIG. 5 is an exploded bottom perspective view thereof;

FIG. 6 is a top plan view thereof;

FIG. 7 is a bottom plan view thereof;

FIG. 8 is a top perspective view of the set of cup and cup holder with the cup holder portion of the set of cup and cup holder removed for clarity of disclosure;

FIG. 9 is an exploded top perspective view of the set of cup and the cup holder shown in FIG. 8;

FIG. 10 is a bottom perspective view thereof;

FIG. 11 is an exploded bottom perspective view thereof;

FIG. 12 is a front elevational view thereof;

FIG. 13 is an exploded side elevational view thereof;

FIG. 14 is a top plan view thereof;

FIG. 15 is a top perspective view of the set of cup and cup holder with the cup portion of the set of the cup and cup holder removed for clarity of disclosure;

FIG. 16 is a bottom perspective view of the cup holder shown in FIG. 15;

FIG. 17 is a front elevational view thereof;

FIG. 18 is a top plan view thereof;

(Continued)

FIG. 19 is a bottom plan view thereof;

FIG. 20 is a top perspective view of a set of cup and cup holder with the cup holder portion of the set of cup and cup holder removed for clarity of disclosure.

FIG. 21 is a bottom perspective view of the cup shown in FIG. 20;

FIG. 22 is a front elevational view thereof;

FIG. 23 is a top plan view thereof; and,

FIG. 24 is a bottom plan view thereof.

Portions of the set of cup and cup holder shown in broken lines from no part of the claimed design.

The right elevational view, the left elevational view, and the rear elevational view of the set of cup and the cup holder are not shown because they are identical to the front elevational view shown in FIG. 2.

The right elevational view, the left elevational view, and the rear elevational view of the set of cup and the cup holder shown in FIG. 1, depicted without a plate, are not shown because they are identical to the front elevational view shown in FIG. 12.

The right elevational view, the left elevational view, and the rear elevational view of the cup holder shown in FIG. 1, depicted without the cup, are not shown because they are identical to the front elevational view shown in FIG. 17. The right elevational view, the left elevational view, and the rear elevational view of the cup shown in FIG. 1, depicted without the cup holder, are not shown because they are identical to the front elevational view shown in FIG. 22.
